UNITED STATES PATENT OFFICE

2,130,943

SINK

Alfred A. Boisvert, Glasgow, Mont.

Application October 28, 1937, Serial No. 171,552

1 Claim. (Cl. 4—187)

The present invention relates to new and useful improvements in sinks and has for one of its important objects to provide, in a manner as hereinafter set forth, a device of this character embodying a drain which is located in an out-of-the-way position at one corner of the sink, thereby materially increasing the usable area of the bottom of said sink and preventing refuse and waste from accumulating on the central portion thereof, as at present.

Another very important object of the invention is to provide a sink of the aforementioned character embodying novel means for receiving the usual refuse, such as peelings, etc., which accumulate during the preparation of a meal and which may be expeditiously emptied and cleaned when desired.

Other objects of the invention are to provide a sink of the character described which will be comparatively simple in construction, strong, durable, highly efficient and reliable in use, sanitary, attractive in appearance and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in front elevation of a sink embodying the present invention.

Figure 2 is a top plan view thereof.

Figure 3 is a vertical sectional view, taken substantially on the line 3—3 of Fig. 2.

Figure 4 is a view in horizontal section, taken substantially on the line 4—4 of Fig. 3.

Referring now to the drawings in detail, it will be seen that the embodiment of the invention which has been illustrated comprises a sink which is designated generally by the reference numeral 1. The sink 1 includes a bottom 2 and the usual inclined walls 3. One corner portion of the walls 3 of the sink 1 is vertical for providing a substantially segmental cylinder 4. This is shown to advantage in Fig. 3 of the drawings. It may be well to here state that the bottom 2 of the sink 1 slopes toward this corner of said sink.

Depending from the bottom 2 in alignment with the segmental cylinder 4 is what may be referred to as an integral well 5 having mounted in the outlet opening 6 in the bottom thereof a strainer 7. The reference numeral 8 designates a drain or waste pipe which is connected to the bottom of the well 5, as at 9.

Suspended in the well 5 and spaced from the walls and the bottom thereof is a removable foraminous basket or receptacle 10. A strainer 11 is removably mounted in the top portion of the receptacle 10. The receptacle 10 is suspended in position in the well 5 through the medium of an external flange 12 which engages on a seat which is provided therefor in the bottom 2 of the sink 1.

It will thus be seen that a sink has been provided wherein the drain is located in one corner where it is out of the way and toward which peelings, etc., will move thereby preventing the littering of the central portion of the sink which, of course, is the portion which is used the most. By removing the strainer 11 the refuse will be collected in the foraminous receptacle 10, as will be readily apparent. The substantially cylindrical corner portion 4 of the sink 1 facilitates removing the receptacle 10 for emptying and replacing said receptacle. This portion 4 also permits the location of the drain in the extreme corner of the sink. The capacity of the receptacle 10 is such that it does not have to be emptied during the preparation of the usual meal. Obviously, the invention may be incorporated in various types of sinks, such as cabinet sinks.

It is believed that the many advantages of a sink constructed in accordance with the present invention will be readily understood and although a preferred embodiment of the device is as illustrated and described, it is to be understood that changes in the details of construction and in the combination and arrangement of parts may be resorted to which will fall within the scope of the invention as claimed.

What is claimed is:—

A sink of the class described including a bottom wall and inclined side walls, one corner of the sink being formed with vertical walls of substantially semi-cylindrical shape in cross section, a cylindrical well depending from said corner of the sink with portions of its side walls forming continuations of the straight walls of said corner portion, a drain pipe connected to the bottom of the well, a removable screen in the bottom of the well covering the drain pipe, the bottom wall of the sink sloping to the well, a perforated receptacle supported in the well with its open top flush with the bottom wall of the sink, and a removable screen extending across the top of the receptacle.
